UNITED STATES PATENT OFFICE

WILFRED ANDREW SHIER, OF BRACEBRIDGE, ONTARIO, CANADA

STERILIZER FOR HAIR CLIPPERS AND THE LIKE

Application filed October 5, 1929. Serial No. 397,600.

My invention relates to improvements in sterilizers for hair clippers and the like, and the object of the invention is to devise a simple device into which hair clippers may be readily inserted without detachment from the driving cable so that the clippers may be readily sterilized and always ready for immediate use, and it consists essentially of the arrangement and construction of parts as hereinafter more particularly explained.

Fig. 1 is a front elevation and mostly in section of my sterilizer showing the clipper head in position.

Fig. 2 is a vertical section through Fig. 1 showing the clipper head in full.

Fig. 3 is a plan sectional view on line 3—3 Fig. 2.

In the drawings like characters of reference indicate corresponding parts in each figure.

1 indicates the body of the sterilizer casing, the front edges of the side walls 1^x and 1° being inclined as indicated in Fig. 2. The top wall 2 is provided adjacent the rear wall 3 with a transverse slotted opening 2^x. 4 is a cover for the opening 2^x hingedly connected to the back wall 3 at 4^x and provided at its free forward edge with an up-turned lip 4°. 5 is a wall extending between the side walls 1^x and 1° and between the top wall 2 adjacent the front edge of the opening 2^x to the bottom wall 6 adjacent the inner end of the slotted opening 6^x and provided in its upper portion with perforations 5^x, by this means a chamber is formed access to which is obtained through the opening 2^x.

This chamber is filled with fibrous absorbent material 8 which is soaked with a suitable antiseptic liquid such as formaldehyde, the fumes from which pass through the perforations 5^x into the main chamber of the casing 1. The forward side edges of the slot 6^x are preferably flared outward as indicated at 6° so as to permit of the clipper head being readily inserted. 9 is a front cover hingedly mounted at 10 to the front end of the top wall 2 and held by gravity against the inclined edges of the side walls 1^x and 1°.

In order to render the device fume tight I preferably provide flaps of felt 11 and 12 at

each side of the slotted opening through which the clipper head 13 is passed so that the shoulder 13^x of the clipper head will rest upon the bottom wall as indicated in Fig. 1 so as to support the head within the main chamber of the casing 1, so as to be exposed to the action of the fumes therein to sterilize it.

The bottom wall 6 is preferably also provided with projections 6° at each side of the slot 6^x adjacent its front edge, such projections being provided with an upwardly and rearwardly inclined upper face thereby forming a shoulder at 7° over which the head is slipped. In inserting the head in position all it is necessary to do is for the operator to grasp the head engaging it with the lower downwardly projecting edge portion of the cover 9 so as to swing it forward and enable the head being passed upwardly into the main chamber of the casing 1 and into the slot 6^x passing it rearwardly so that the shoulders of the head rest upon the bottom wall 6 at each side of the slot 6^x, the inclined upper face of the projection 6° permitting of its slipping unobstructedly to its supported position.

The casing 1 may be carried on any suitable rod standard and clipped thereto by means of the clipped bracket 14. If desired the edges of the covers 9 and 4 may be also provided with felt so as to minimize the escape of fumes from the main chamber of the casing.

From this description it will be seen that I have devised a very simple device whereby clippers and like articles may be readily sterilized and held always ready for use.

What I claim as my invention is:—

1. A sterilizer for hair clippers and the like, comprising a main casing having an open front and an open ended slotted bottom, and having a transverse slot in the top wall of the casing adjacent the back wall, a perforated wall extending between the side walls and the casing and between the top and bottom wall adjacent the front edge of the transverse opening and the rear edge of the bottom slot and adapted to be filled with fibrous absorbent material soaked in vaporizable liquid, a hinged cover for the transverse opening, and a hinged cover for the open front of the cas-

ing adapted to extend at its lower edge below the bottom wall of the casing.

2. A sterilizer for hair clippers and the like, comprising a main casing having an open front and an open ended slotted bottom, and having a transverse slot in the top wall of the casing adjacent the back wall, a perforated wall extending between the side walls and the casing and between the top and bottom wall adjacent the front edge of the transverse opening and the rear edge of the bottom slot and adapted to be filled with fibrous absorbent material soaked in vaporizable liquid, a hinged cover for the transverse opening, a hinged cover for the open front of the casing adapted to extend at its lower edge below the bottom wall of the casing, and projections extending from the bottom of the casing at each side of the front portion of the slot having inclined upper faces behind which the shoulders of a clipper head are adapted to fit and rest upon the bottom wall of the casing at each side of the slot.

WILFRED ANDREW SHIER.
